UNITED STATES PATENT OFFICE.

CHARLES EUGENE SWIFT, OF DANVILLE, ILLINOIS.

BINDER.

1,078,470.

Specification of Letters Patent. Patented Nov. 11, 1913.

Application filed December 5, 1912. Serial No. 735,042.

To all whom it may concern:

Be it known that I, CHARLES E. SWIFT, a citizen of the United States, and a resident of Danville, in the county of Vermilion and State of Illinois, have invented a new and Improved Binder, of which the following is a full, clear, and exact description.

My invention relates to loose leaf binders, and is especially intended to produce a binder adapted to receive loose leaves consisting of cardboard or like mounts bearing blue prints on opposite sides.

The invention will be more particularly explained in the specific description herein- after to be given.

Reference is to be had to the accompanying drawings forming a part of this specification, in which similar characters of reference indicate corresponding parts in all the views.

Figure 1 is a plan view of a binder embodying my invention, parts being broken away, the covers being shown opened; Fig. 2 is a transverse vertical section on approximately the line 2—2 of Fig. 1; Fig. 3 is a fragmentary view similar to Fig. 2, of the central portion of the binder, the arched impaling post being shown with the rockable section thereof in the open position; and Fig. 4 is a transverse vertical section of the binder closed.

In forming a binder in accordance with the illustrated example, covers 10 of any suitable material are flexibly united to a back 11, and rigidly secured to said back, longitudinally thereof, is a base 12, consisting of a strip of wood or metal. To the base strip 12, along one edge thereof, is a series of fixed sections 13 of arched impaling posts.

Each impaling post comprises in addition to the rigid section 13, which may be integral with the base strip 12, or secured thereto, a rockable impaling post section 14, said rockable sections being in fixed relation to a rock bar 15 held by staples 16 or equivalent means, in a longitudinal groove 12^a along that edge of the base strip 12 opposite to the lower ends of the fixed impaling post section 13.

The rockable section 14 moves in the plane of the fixed section 13, the two forming a complete arch which springs from the base strip 12 and ranges transversely thereof. Each rockable section 14 is formed with an integral foot 17 extending inward beyond the rock bar 15, over the base 12, against

which foot a spring 18 bears, the spring being preferably a plate spring riveted as at 19 to the base strip 12. When in the closed position of the rockable section 14, the spring 18 bears against the side surface of the foot 17 (see Figs. 2 and 4), while in the open position of the rockable section the end surface of the foot 17 contacts with the spring 18, as in Fig. 3, so that the spring 65 will act to hold the rockable impaling post section 14, either in the open or closed position, and a rocking of the bar 15 by grasping any one of the rockable sections, will move all the rockable sections either against 70 the fixed sections 13, or away from the latter. The integral feet 17 are received in transverse depressions 12^b formed in the top surface of the base complementary to the longitudinal groove or concavity 12^a. It 75 will be observed that a fixed impaling post section 13 arches over the base strip 12, from one side edge thereof to a point approximately above the opposite side edge, and terminates in a downward curve.

In order to bind blue prints in my improved binder, leaves 20 are provided, of cardboard, stiff paper, or equivalent material, one leaf being shown in Figs. 1 to 3, and on each face of a leaf 20, a blue print 80 21 may be mounted, as shown in Fig. 1, preferably by pasters 22 at the corners of the blue print. Each leaf has holes 23 near the inner edge, as indicated in Fig. 2, so that the leaves may swing on the impaling 85 post sections from one side of the binding post to the other, and they may be removed from the impaling posts, or placed thereon when the rockable sections 14 are moved to the open position.

My improved binder and mounts it will be observed has a capacity and form such that a large number of blue prints may be assembled in a single binder and accessible for convenient examination.

Having thus described my invention, I claim as new and desire to secure by Letters Patent,—

In a binder, the combination with a back, covers flexibly connected with the back, and a rigid flat base strip secured to the inner face of the back; of holding means on said base strip for loose leaves, said means comprising divided, arched, impaling posts, one section of each of which is immovably secured to the base strip at the back edge thereof, a rockable rod to which the mating

section of each post is connected, to be rocked toward or from the fixed section, the base strip having a longitudinally ranging concavity therein at the upper side thereof, at the front edge; and springs secured at one end of each to the base strip on the upper side of the latter, and ranging forwardly, the rockable sections of the impaling posts having extensions at their lower ends disposed beneath the springs, and the

base strip having in the upper side thereof depressions for said extensions complementary to the longitudinal concavity.

In testimony whereof I have signed my name to this specification in the presence of 15 two subscribing witnesses.

CHARLES EUGENE SWIFT.
